UNITED STATES PATENT OFFICE.

DARIO ROBERTI, OF SPRINGFIELD, MASSACHUSETTS.

COMBINATION LOCK.

Application filed February 26, 1925. Serial No. 11,630.

To all whom it may concern:

Be it known that I, DARIO ROBERTI, a subject of the King of Italy, residing at Springfield, in the county of Hampden and State of Massachusetts, have invented a new and useful Combination Lock, of which the following is a specification.

My invention relates to improvements in combination locks designed more especially for steering-posts of automobiles, and consists generally of a box secured to the instrument-board adjacent to the steering-post of an automobile, a lock case receivable in said box, and having a hinged back plate or cover, lock mechanisms in said case, said mechanisms comprising a bolt for said steering-post, and one or more bolts for locking said case to said box, retracting means for said bolts, a latch to retain said bolts in retracted position, one or more lock-rods or bars to secure or lock said bolts in projected position, a supporting and shift bar for the lock-bars, a corresponding number of lifter-rods or bars for said lock-bars, in connection with which may be used a dummy lifter-bar, mechanism to impart a step-by-step movement upwardly to said lifter-bars, releasing means for said lifter-bars when elevated, a latch for said case, and latches for said cover, together with such other parts and members as may be necessary or desirable in order to render the combination lock complete and serviceable in every respect, all as hereinafter set forth.

One object of my invention is to produce a combination lock for the steering-post of an automobile, which lock is adapted to be unlocked by having imparted to each of the lifter-bars, through the medium of push-pins, which correspond in number with the lifter-bars, a predetermined number of pulsations, whereby all bolts are released and can be withdrawn from locking position. Thus it is seen that only a person having the correct combination can release the steering-post from the lock, and unlock the case from the box which is secured to the instrument-board.

Another object is to afford means for readily attaching this lock to the instrument-board in proper or operative position relative to the steering-post.

A further object is to render the lock entirely safe, as well as secure, to the end that there is no liability of the bolt for the steering-post being released, when in re-

tracted position, and so accidentally engaging and locking said steering-post.

Still another object is to afford means for obtaining access to the interior of the case for the purpose of changing the combination of the lock, without, however, detracting from or decreasing the safety or security of the lock. It is to this end that provision is made for locking the case to and unlocking it from the box.

A still further object is to provide the lock case with means to retain it in the box at such times as said case is unbolted from said box.

Other objects and advantages will appear in the course of the following description.

Attain the objects and secure the advantages of my invention by the mechanism illustrated in the accompanying drawings, in which—

Figure 1 is a front elevation of a combination lock which embodies a practical form of my invention, showing the same attached to the instrument-board and in locking engagement with the steering-post of an automobile; Fig. 2, a vertical section through said instrument-board and the box for the lock case, looking toward the left; Fig. 3, a similar section but looking toward the right; Fig. 4, a rear elevation of said lock case; Fig. 5, a top plan of the engaging member for said steering-post, such member having a bifurcated instead of a cylindrical head; Fig. 6, a top plan of the supporting and shift bar for the lock-bars; Fig. 7, an enlarged top plan of one of the cover latches; Fig. 8, an enlarged sectional detail illustrating the action of the lifting mechanism; Fig. 9, an enlarged vertical section through the lock case and its contents, to assist in an understanding of which reference should be made to lines 9—9, looking in the direction of the associated arrows, in Fig. 12; Fig. 10, an enlarged sectional detail illustrating the manner in which the lifter-bars are released from their detents; Fig. 11, an enlarged vertical section through the latch that holds the bolts in retracted position, and, Fig. 12, an enlarged rear elevation of the lock case open, with parts broken away and in section.

In the first view portions of the box lug and instrument-board are broken away, and the steering-post members are in cross section.

Similar reference characters designate

similar parts throughout the several views.

In Figs. 1 and 3 fragmentary parts of an automobile instrument-board, a steering-post, a steering-post tube, and a supporting sleeve are represented at 1, 2, 3, and 4, respectively, said steering-post having a collar 5 secured thereto. A box 6 having flanges and a plate or flat lug, which extend onto the front side of the instrument-board 1, is let into an opening provided to receive the same in said instrument-board at the left of the steering-post 2. The aforesaid flat lug extends over the instrument-board 1 to the right from the box 6, and is designated by the numeral 7. The tube 4 passes through the lug 7, and the sleeve 4 is mounted on said lug and with the latter bolted to the instrument-board. In this manner and by this means the box 6 is securely fastened to the instrument-board. There is an opening 8 in the right-hand side of the box 6, to the right of said opening an opening 10 in the instrument-board 1, and to the right of the opening 10 an opening 11 in the tube 3. These openings are in communication with each other, and a lateral opening 12 in the steering-post 2 and collar 5 is so located that it is brought into communication with the other openings when said steering-post is turned to position the front wheels in some certain situation relative to the back wheels of the machine, as in line therewith, or straight ahead. In the left-hand side of the box 6 are two bolt holes 13, and in the opposite side of said box are two other holes 14. A lug 15 extends inwardly from the left-hand side of the box.

The box 6 is open in front, and fitting into said box, with flanges on the front to overlap the edges of the box opening, is a lock case 16. The case 16 is open behind and provided with a plate or cover 17 to close the opening, said cover having its bottom edge hinged at 18—18 to the rear edge of the bottom side of said case. On the left-hand side of the case 16 are two lugs 19 through which bolts 20—20 extend and from which they may be projected into the holes 13 in the box 6, and there is a latch 21 which extends from the same side of the case to engage behind the lug 15, when the case is in the box. Projecting from the right-hand side of the case 16 are two lugs 22 which are adapted to enter the holes 14 in the box 6, and a sleeve 23 which is adapted to enter the openings 8, 10, and 11, when said case is inserted in said box. The openings 8, 10, and 11 are so located and of such proportions and the size of the box 6 inside is such as to enable the case 16 to be placed in position in and removed from said box. The lugs 19 are tapered for the purpose, also, of facilitating the insertion and removal of the case in and from the box. The

lugs 19 project far enough, to engage the left-hand side of the box, when the case is in place therein, and so prevent said case from moving either to the right or left in said box. The bottom parts of the hinges 18 are received on the bottom of the box and the top of the case contacts with the top of the box, consequently there can be no vertical movement of the case in the box. Within the sleeve 23 is a bolt 24 that is capable of being thrust into the steering-post opening 12.

The case 16 is inserted in the box 6 while the bolts 24 and 20 are in retracted position, the lugs 22 then entering the holes 14 and the latch 21 snapping into engagement with the lug 15. Thus the case is held securely in the box without the aid of the bolts 20. When, however, the bolts 20 are thrust into the holes 13, which is done at the time the bolt 24 is thrust into the hole 12 to lock the steering-post 2, the case 16 is locked in place and can not be removed from the box 6. After the bolts 20 have been withdrawn from the openings 13, which occurs at the time the bolt 24 is withdrawn from the opening 12, the case can be removed from the box simply by actuating the latch 21 out of engagement with the lug 15, through the medium of a knob 25, and pulling said case out while still retaining hold of said knob. The left-hand side of the case is withdrawn first, and the right-hand side of the case is inserted first.

The knob 25 is in front of the case 16. 100 A spindle 26 extends rearwardly from the knob 25, through the front side of the case 16 and a bracket 27 with which said case is provided, and an operating-arm 28 is secured to said spindle within the case—see 105 Fig. 12. The arm 28 is bifurcated and engages a portion of the latch 21 which extends into the case, and is slotted or recessed on each side, as represented at 29, to provide shoulders on both sides for the fork of said arm to engage with or bear against. A rod 30 extends inwardly from the latch 21, and is supported by another bracket 31 with which the case is provided. A spiral spring 32 encircles the rod 30 between the inner 110 end of the latch 21 and the inner end of the bracket 31, and normally retains said latch in projected position. Upon partially rotating the knob 25 in the direction to actuate the arm 28 inwardly, through the medium of the spindle 26 to which bolt said knob and arm are secured, the resiliency of the spring 32 is overcome and the latch is retracted and caused to disengage the lug 15. When the knob 25 is released the spring 32 restores the latch to its former advanced position.

There are on the front of the case 16, in addition to the knob 25, a knob 33, a latch handle 34, the heads of five push-pins 35, 130

a releasing- or drop-bar 36, and an operating lever or handle 37 for said drop-bar.

The knob 33 is secured to the front end of a spindle 38 that is journaled in the front side of the case 16 and a lug 39 behind, and secured to the inner end of said spindle is a downwardly-extending operating arm 40—see Fig. 12. The knob 33 is between the vertical planes of the knob 25 and the handle 34.

The handle 34 is rigidly attached to a lug 41 that extends forwardly from a vertical latch 42. A bracket 43 is fastened to the front side of the case 16, inside of said case, and has upper and under, inwardly-extending lugs 44 and 45, respectively, which have openings therein to receive the upper and lower terminals of the latch 42. Both the front side of the case 16 and the bracket 43 are slotted vertically, as represented at 46, to receive the lug 41. Projecting from the latch 42 above the lug 45 is a lug 47, and a rod 48 extends upwardly from said first-named lug through the opening in the lug 44 above. A spiral spring 49 encircles the rod 48 between the lugs 47 and 44, and tends constantly to force the latch 42 downwardly as far as the lug 45 permits. All of these parts and members are shown in Figs. 11 and 12. When the lug 47 is on the lug 45, the lug 41 is at the bottom of the slot 46, and the base of the latch 42 extends below said lug 45. By moving the handle 34 upwardly, against the resiliency of the spring 49, the latch 42 is elevated and the lower end thereof carried up into the opening in the lug 45.

The arm 40 and the latch 42 at their lower ends are in operative position relative to a shank 50 from the right-hand end of which the bolt 24 extends, said shank being hereinafter described in detail.

On the back side of the cover 17 near the top are two horizontal slides 51, a resilient operating arm 52, and a stop pin 53 for said arm.

The slides 51 are provided at their inner ends with forwardly-extending lips, and there are two longitudinal slots 55 in said slides adjacent to said lips. Behind each slide 51, adjacent to the outer terminal thereof, is a slot 56 in the cover 17, one of said slides being broken off in Fig. 4 to show in full the slot above. Two horizontal latch bolts 57 are arranged in keepers 58—58 behind the slots 56, as shown in Fig. 12. Two screws 59 pass through the slots 55 to be tapped into the covers 17, and two screws 60 pass through the slides 51 and the slots 56 to be tapped into the latch bolts 57. Thus the slides 51 are supported and longitudinal movement is permitted both to the slides and the bolts. The keepers 58 are fastened to the cover 17 on the inside, and springs 61—61 are provided normally to retain the

bolts 57 in advanced position. Recesses 62—62 are made in opposite sides of the case 16 to receive the terminals of the bolts 57 which protrude from the keepers 58 at their outer ends. Each spring 61 is wound around a pin 63 set in the cover 17, and one terminal of said spring bears against the inner end of the adjacent bolt 57, while the other terminal of said spring bears against the top of a lug 64 with which said cover 70 is provided below said pin. Each bolt 57 has at the inner end a downwardly-extending projection 65 which strikes the inner end of the keeper 54 for said bolt, when the latter is released to its spring 61, and thus 75 limits the outward movement of the bolt.

Upon closing the cover 17 the bolts 57 snap into the recesses 62 and thus lock said cover to the case 16. To release or unlock the cover 17 from the case 16, simply press 85 toward each other the lips 54 and the slides 51, and thus withdraw the bolts 57, which are connected with said slides by means of the screws 60, from the recesses 62, the bolts then being actuated inwardly against 90 the resiliency of the springs 61. Upon releasing the lips 54 the springs 61 immediately actuate the bolts 57 outwardly and into position to snap into the recesses 62 when next the cover is closed.

It should be remembered that, since the cover 17 is open in Fig. 12, the top of said cover is at the bottom of that view.

At the top of the cover 17 on the inside is a lip or flange 66, and this flange fits into a cut-away portion 67 of the top of the case 16, when said cover is closed. The keepers 58, the pins 63, and the lugs 64 are all below the flange 66, and a series of pins 68 are set in the under side of the flange. A stop 69 projects inwardly from the cover 17 below one of the keepers 58, and journaled in said cover below the same keeper is a spindle 70 to the outer end of which is secured the arm 52, and to the inner end of which is secured 105 an actuating lever 71. These parts and members are adjacent to the side of the cover and case where are located the bolts 20 and the latch 21. The stop pin 53 is in the path of the arm 52, the lever 71 has a head by means of which said lever is directly mounted on and secured to the spindle 70, and the stop 69 is in the path of a shouldered part of said head, as clearly shown in Fig. 12.

When the resilient arm 52 is positioned below the pin 53, as in Fig. 4, the head of the lever 71 is in contact with the stop 69, and said lever is approximately parallel with the adjacent side of the cover 17, and when said arm is moved to locate it on the other side of said pin, said head is rocked upwardly away from said stop, and said lever is carried inwardly at the bottom.

A horizontal supporting and shift bar 72 130

is held in place against the front faces of the lugs 64 by means of two pins or screws 73 which pass through oblique slots 74 in said bar. The terminal of the bar 72 that is adjacent to the lever 71 is bent rearwardly, as represented at 75 in Figs. 6 and 7; and such rearwardly-extending part is retained in contact with the lever 71 by means of a spiral spring 76. The spring 76 encircles a rod 77 which has one end pivotally connected at 78 with the lug 64 that is adjacent to the part 75, and the other end passed through said part, and said spring bears between said lug and said part. The bar 72 is permitted to be moved on the screw 73, and such movement is oblique because of the oblique slots 74 through which said screws pass. Normally the bar 72 is supported on the screws 73 by the tops of the slots 74, the force of the spring 76 being then absorbed by the lever 71 and the stop 69. At this time the resilient arm 52 is below the stop pin 53. When, however, the arm 52 is moved to the other side of the pin 53, the spindle 70 is rocked and the lever 51 rocked with it in the direction to force the bar 72 toward the side of the cover and case where are located the bolt 24, and at the same time said bar is caused to ascend until the bottoms of the slots 74 are in contact with the screws 73. The return of the arm 52 to the under side of the pin 53 permits the spring 76 to actuate the bar 72 in the opposite direction and downwardly as far as the tops of the slots 74 and the stop 69 and intervening parts and members permit.

The cover 17 on the inside is provided with two narrow outside ribs 79 and four wide intermediate ribs 80 which extend from the flange 66 downwardly nearly to the bottom of said cover. These ribs are spaced from each other, the ribs 79 are undercut beneath their inner longitudinal edges, and the ribs 80 are undercut beneath both longitudinal edges, whereby are formed five, vertical, T-shaped ways or grooves. The lugs 64 are secured directly to the ribs 79. Arranged to slide in the T-shaped grooves provided by the ribs 79 and 80 are lock-bars 81. There may be one of the lock-bars 81 in each groove, but in the present example there are no lock-bars in two of the grooves. Each of the lock-bars is T-shaped in cross section, and normally it is positioned behind the bar 72, and supported by said bar through the medium of a pin 82 which projects forwardly from the lock-bar near the upper end thereof. A spiral spring 83 is interposed between the flange 66 and each lock-bar 81 to assist gravity in forcing the same downwardly. The pins 82 are in position to center the springs 83 at the top. The lower terminals of the springs 83 are let into the lock-bars 81 at

their upper ends. In this case the lock-bars 81 are in the two outermost grooves and the groove which is nearest adjacent to one of said outermost grooves.

Lifter-bars 84, 85, and 86 are slidingly arranged in the grooves in which are located the lock-bars 81, and below the latter. These lifter-bars are of different lengths, each is cut back at the upper terminal to form a thin projection 87, and all have ratchet-teeth 88 on their front sides. The ratchet-teeth 88 extend upwardly from the bottom of each lifter-bar for a considerable portion of the length thereof. Each of these lifter-bars is T-shaped and similar in size, in cross section, like and to the lock-bars 81. In the front sides of the lifter-bars 84, 85, and 86, above the ratchet-teeth 88, are three punch marks, one punch mark, and four punch marks, respectively. A dummy lifter-bar 89 is also provided and the same is located in one of the grooves in which there is no lock-bar. The lifter-bar 89 is generally similar to the other lifter-bars except that it has no projection 87. The dummy lifter-bar is marked with an α . Normally all of the lifter-bars rest on the bottom of the case 16, and their lengths are such that then they are out of contact with the lock-bars 87. The lock-bars are of such length that they now extend some distance below the bar 72. A notch 90 is cut in the bar 72 from below to accommodate the lug 47 of the latch 42.

There may be more or less than four ribs 80, lock-bars and lifter-bars may be provided for all or a less number of the grooves formed by said ribs and the ribs 79, and, if some of the lock-bars are omitted, one or more dummy lifter-bars may be employed.

The shank 50 of the bolt 24 is supported against the inner face of the front side of the case 16 by means of a guide-bar 91 and two screws 92. The guide-bar 91 is T-shaped in cross section, and there is a longitudinal slot 93 in the shank 50 to receive the narrow part of said guide-bar, said slot being long enough to enable the shank 50 to move longitudinally to the extent required. The screws 92 pass through the guide-bar 91 to be tapped into the front side of the case 16. At the bolt end of the shank 50, on the back side, is a lug 94, and at the opposite end of said shank, also on the back side, are two nose-pieces 95, one above the other. A spring 96 has one end secured to a post 97 set in the front side of the case 16 and extending inwardly, said spring is given several turns around said post, and the free end of said spring bears against the inner side of the lug 94. Thus the spring 96 tends constantly to urge the shank 50 in the direction to project the bolt 24. The shank 50 has a rearwardly-projecting flange 98 at the top, and in this flange are slots 99 and 100,

and notches 101, the latter being in the back edge of said flange, and corresponding in number with the number of lock- and lifter-bar grooves. The lower terminal of the arm

5 40 extends into the slot 99, and the bolt 24 is retracted by swinging said arm in the direction to actuate the shank 50 toward the left (toward the right in Fig. 12), sufficient force being used to overcome the resistance 10 of the spring 96. The slot 100 is in position to receive the bottom end of the latch 42 at this time, and said latch then holds the parts in retracted position, as shown in Fig. 12.

U-shaped brackets 102—102 are attached

15 to the left-hand side of the case 16, above and below the nose-pieces 95, two levers 103 are pivotally connected, intermediate of their ends, with said brackets, at 104—104. Adjacent terminals of the levers 103 are in the 20 paths of the nose-pieces 95. The other terminals of the levers 103 are bifurcated to engage portions of the bolts 20 which extend into the case 16, and are slotted or recessed on opposite sides, as represented at 105,

25 Fig. 12, to provide shoulders on both sides to be engaged by the forks of said levers. Rods 106—106 extend inwardly from the bolts 20, and are supported by brackets 107—107 attached to the case above and below the brackets 102. Spiral springs 108—108 encircle the rods 106 between the inner ends of the bolts 20 and the inner ends of the brackets 107, and tend constantly to force the bolts 20 outwardly.

30 Obviously, the bolts 20 are retracted simultaneously with the bolt 24, because, when the shank 50 is actuated to draw said bolt 24 inwardly, the nose-pieces 95 of said shank rock the levers 103 on their pivots 104 in the directions to force said bolts 20 inwardly against the resiliency of the springs 108.

Upon the withdrawal of the latch 42 from engagement with the shank 50, the latter is 35 released to the spring 96 which immediately actuates said shank in the direction to advance the bolt 24, and to release the bolts 20 to the action of the springs 108, whereby said bolts 20 are advanced. The last-mentioned action is brought about by the inward movement of the nose-pieces 95 and the resulting movement on the part of the levers 103 under the influence of the springs 108.

The notches 101, in the bolt-shank flange 40 98, equal in number the full quota of lock-bars 81, and said notches are so located that, when the shank 50 is in what may be termed retracted position, said notches are directly opposite the spaces between said lock-bars, and, when said shank is in what may be termed advanced position, said notches are in position to receive said lock-bars and the lifter-bars. It follows, therefore, that, when any lock- or lifter-bar is in 45 any notch 101, the shank 50 is thereby pre-

vented from being actuated into retracted position, but that upon so arranging said lock- and lifter-bars that there is a clear passage for the flange 98 below the lower ends of the lock-bars and above the upper 70 ends of the lifter-bars, said shank can be actuated from advanced to retracted position.

When the cover 17 is closed, the bar 72 passes above the shank 50, and the back edge of the flange 98, at points between the notches 101, encounter the lock-bars 81 unless they be elevated a sufficient distance to prevent contact therewith by said flange, assuming, of course, that said shank is in retracted position. Such contact as 80 has just been mentioned is avoided, however, by operating the resilient arm 52 in the manner to raise the bar 72 and elevate the lock-bars 81. As soon as the cover 17 is closed, the arm 52 is returned to its former position, 85 and the bar 72 is permitted to move downwardly again and the lock-bars to descend until they rest on the flange 98 between the notches 101, there to remain until the shank 50 moves into advanced position, when said lock-bars drop as far as the pins 82 permit, with the lower terminals of said lock-bars in said notches. Meanwhile the lifter-bars are resting on the bottom of the case 16.

90 In order to unlock the shank 50 so as to enable the knob 33 to be actuated to cause said shank to be moved into retracted position, it is necessary to remove all of the lock-bars 81 from the notches 101, through the medium of the lifter-bars 84, 85, and 86, without thrusting any of said lifter-bars into any of said notches, or thrusting the dummy lifter-bar 89 into the notch which is above the same. The mechanism for doing this work will next be explained.

95 As best shown in Fig. 8, each push-pin 35 is loosely received in a slot 109 in the front side of the case 16, it is rigidly secured inside of said case to a spring 110 which normally retains said push-pin in the outwardly or fully projected position, and a pawl 111 has its lower terminal pivotally connected at 112 with the push-pin. The upper terminal of the spring 110 is fastened 100 to the front side of the case 16 behind, and the push-pin 35 is attached to the lower terminal of said spring. The positions of the push-pin and its pawl 111 are such that the latter engages the ratchet-teeth 88 on the associated or adjacent lifter-bar (84, 85, 86, or 89), and a spiral spring 113 is arranged 105 between the upper terminal of said pawl and the spring 110 to retain the pawl in engagement with the lifter-bar behind, the pawl and spring 110 being respectively provided with centering pins 114 and 115 for 110 said spring 113. Each time, therefore, that any push-pin 35 is forced inwardly, against the resiliency of its spring 110, the pawl 111 115 connected with said push-pin actuates up-

wardly the lifter-bar with which said pawl is in engagement, the arrangement and proportion of the parts being such that the amount of upward movement thus imparted to the lifter-bar is approximately equal to the distance between two of the teeth 88. After the push-pin is thrust inwardly the pressure thereon is removed to permit the spring 110 to which said push-pin is attached to act and carry the push-pin outwardly again.

The drop-bar 36 has at the ends two rigidly attached arms 116 which extend rearwardly from said drop-bar through slots in the front side of the case 16, wherein said arms are pivoted at 117—117 to two lugs 118 secured to said front side behind, as illustrated in Figs. 9, 10, and 12. One of the slots for the arms 116 is indicated by dotted lines 119 in Figs. 9 and 10. From the pivots 117 the arms 116 project upwardly, and a horizontal rod 120 extends between such projection and to which said rod is affixed. A spring 121 has its bottom edge portion clamped between the inner face of the front side of the case 16 and a bar 122, screws 123 being employed to fasten said bar and said spring to said front side. The spring 121 extends rearwardly over the top of the bar 122, then upwardly in front of the rod 120, and finally upwardly and rearwardly, and said spring above said bar has openings cut therein and is cut transversely to form detents 124, there being as many of such detents as there are lifter-bars in their full quota, or five in this case. Normally the detents 124 are in engagement above the slots 111 with the lifter-bar ratchet-teeth 88, and each lifter-bar is held by its detent, after being elevated the distance between two of the ratchet-teeth by the engaging pawl, while the latter is operated to engage the next ratchet-tooth below. When any lifter-bar is elevated, its ratchet-teeth snap past the engaging detent. It is now clear that the lifter-bars are elevated by a step-by-step movement.

A link 125 has its rear end pivotally connected at 126 with a lug 127 on the front of the case 16, passes through a slot 128 in the drop-bar 36, and has the handle 37 pivoted at 129 to the forward end thereof. The pivoted terminal of the handle 37 is bifurcated to receive the front end of the link 125, and the free ends of the bifurcated portion are adapted to bear on opposite sides of the slot 128 when said handle is swung upwardly, and to exert a cam action on the drop-bar. Normally the handle 37 hangs down, and the spring 121 causes the detents 124 to bear against the lifter-bar ratchet-teeth 88, and the drop-bar 36 to be in raised position with its transverse dimension approximately parallel with the front of the case. When, however, the handle 37 is

swung downwardly on the pivot 129, the bifurcated terminal of said handle contacts with the drop-bar 36 and forces the same downwardly and into an inclined position, as shown in Fig. 10, with the result that the arms 116 carry the rod 120 forwardly, and the latter forces the detents 124 out of engagement with the lifter-bars and the lifter-bars immediately drop by gravity onto the bottom of the case. Upon swinging the handle 37 down into its former position, the drop-bar 36 is released to the action of the detent spring, and said spring actuates the arms 116 in such a manner that said drop-bar is carried upwardly, and the rod 120 is carried rearwardly, with the result that the detents 124 reengage the lifter-bar ratchet-teeth.

Assuming that the case 16 is in place in the box 6, the locking and unlocking operations are described as follows:

The handle 34 is raised to withdraw the latch 42 from the slot 100, when the spring 96 acts on the shank 50 to "shoot" the bolts 24 and 20. Now the steering-post 2 can not be turned on its axis, and the case 16 can not be removed from the box 6, until the combination is "worked". The combination is worked by imparting, through the medium of the push-pins 35 and pawls 111, three pulsations to the lifter-bar 84, one pulsation to the lifter-bar 85, and four pulsations to the lifter-bar 86. These pulsations cause the three lifter-bars just mentioned to be raised into contact with the lock-bars 81, and to raise the latter far enough to clear the flange 98, without thrusting any lifter-bar into any notch 101. Due to the presence of the projections 87 at the upper ends of the active lifter-bars, whereby the latter are enabled to contact with the lock-bars 81 while at the same time leaving open spaces in front between the upper and under members, there is now an unobstructed passage for the shank 50 between the lock-bars and said lifter-bars. If any active lifter-bar be raised too far it enters the notch 101 above and prevents the bolt shank from being moved, and if any active lifter-bar be not raised far enough the lock-bar above does not clear the notch 101 into which it extends; and if the dummy lifter-bar be raised even one point it enters the notch 101 with which the same is in line and blocks the movement of said shank.

When the combination is set, the knob 33 is turned to withdraw the bolts and thus unlock both the steering-post 2 and the case 16.

If it be desired to change the combination, the case 16 is unlatched and removed from the box 6, while the bolts are in retracted position, the cover 17 is opened, the lifter-bars are rearranged, or new ones of different lengths from the others are in-

serted, the bar 72 is operated to take the lock-bars 81 out of the way of the shank flange 98, said cover is closed, and said bar 72 is again shifted to permit said lock-bars to descend onto said flange, and then, when the bolts are shot the next time, said lock-bars will drop into the notches 101.

10 Each time the bolts are shot into place, or before attempting to set the combination, the handle 37 is swung up and down for the purpose of distributing the combination and restoring the normal relationship between the detents 124 and the lifter-bar ratchet-teeth.

15 As illustrated in Fig. 5, a forked bolt or bolt-head 130 may be substituted for the cylindrical bolt 24, in which event the steering-post, as 200, is slabbed off on opposite sides to enable the same to be engaged and held by said bolt-head. Otherwise there is no change in the parts and members of the lock.

If desired, the detent spring may be augmented, for the purpose of increasing the force with which the drop-bar 36 is normally retained in its raised position, by providing a spring 131 at each end of the operating mechanism for the detents. Each spring 131 is wound around one of the pivots 117, and arranged with one terminal bearing against the front side of the case 16, and the other terminal bearing in against the front of the adjacent protruding terminal of the rod 120, which rod extends beyond both arms 116.

More or less change in the shape, size, construction, and arrangement of some or all of the parts of this lock, in addition to those hereinbefore specifically pointed out, 40 may be made without departing from the spirit of my invention or exceeding the scope of what is claimed.

What I claim as my invention, and desire to secure by Letters Patent, is—
45 1. The combination, in a lock of the class described, with a box, of a lock case provided with steering-post- and box-engaging bolts, and with a box-engaging latch, said case being receivable in said box, means to lock
50 and release said bolts, and means to withdraw said box-engaging bolts from locking engagement from said box, the construction and arrangement of parts being such that, when the box-engaging bolts are withdrawn,
55 said latch normally retains said case in place in said box.

2. The combination, in a lock of the class described, with a box open in front, of a lock case receivable in said box, having an inner side that opens, and provided with steering-post- and box-engaging means, and means to lock and release said bolts.

65 3. The combination, in a lock of the class described, with a box open in front, of a lock case having one side open, and a cover for

said open side, said case being receivable in said box, and provided with steering-post and box-engaging bolts, means to secure said case to said box in the side opposite to said box-engaging bolts, which means is entirely disconnected when said bolts are retracted and the case is taken from the box, and means to project and retract said bolts. 70

4. The combination, in a lock of the class described, with a box open in front, of a lock case receivable in said box and when therein being held against movement up or down or sideways by the top, bottom, and sides of said box, and provided with steering-post- and box-engaging bolts, and with releasable means other than the box-engaging belt normally to prevent said case from being removed from said box, and means to lock and release said bolts. 75 80

5. The combination, in a lock of the class described, with a box open in front, of a lock case receivable in said box, and provided with bolts to engage the steering-post and said box, a shank for said steering-post-engaging bolt, means to operate said shank, means to lock and release said shank, and a lever connected with said box-engaging bolt and extending into the path of said shank.

6. The combination, in a lock of the class described, with a box open in front, of a lock case receivable in said box, and provided with bolts to engage a steering-post and said box, springs arranged to advance said bolts, a shank for said steering-post-engaging bolt, means to actuate said shank into retracted position, means to hold said shank in such position, means to lock and release said shank when in advanced position, and a lever connected with said box-engaging bolt and extending into the path of said shank, whereby when said shank and steering-post-engaging bolt are retracted said box-engaging bolt is retracted, and when the former are advanced the latter is advanced. 100 105 110

7. The combination, in a lock of the class described, with a lock case, and a spring-pressed bolt shank in said case, said shank having a perforated and notched flange, of rotatable means journaled in the front of said case and consisting in part of an arm which has one end in one of the perforations in said flange, a spring-pressed latch mounted in and having a handle on the outside of said case, said latch being adapted to enter the other perforation in said flange when said shank is retracted, and locking and releasing permutation elements in said case for said shank, said elements being adapted to enter the notches in said flange.

8. The combination, in a lock of the class described, with a lock case provided at the back with a cover, of bolt mechanism and permutation locking and releasing mechanism therefor in said case, said last-named

mechanism consisting in part of lock- and lifter-bars carried by said cover.

9. The combination, in a lock of the class described, with a lock case provided at the back with a cover, latches arranged to retain said cover in closed position, and operating means for said latches, of bolt mechanism and permutation locking and releasing mechanism therefor in said case, said last-named mechanism consisting in part of lock- and lifter-bars, carried by said cover.

10. The combination, in a lock of the class described, with a lock case provided at the back with a cover, of a notched bolt shank, operating means for said shank, lugs on said cover, a spring-pressed bar having oblique slots therein, screws passing through said slots into said lugs, lock-bars supported by said first-named bar, a spindle journaled in said cover, a lever secured to the inner terminal of said spindle and in contact with said first-named bar, and an arm secured to the outer terminal of said spindle, the construction and arrangement of parts being such that, when said arm is moved in one direction, said first-named bar is shifted to move said lock-bars out of the way of said shank, and, when said arm is moved in the other direction, said first-named bar is shifted to permit said lock-bars to assume their former positions.

11. The combination, in a lock of the class described, with a lock case provided at the back with a cover, of a notched bolt shank, operating means for said shank, lugs on said cover, a spring-pressed bar having oblique slots therein, screws passing through said

slots into said lugs, lock-bars supported by said first-named bar, a spindle journaled in said cover, a lever secured to the inner terminal of said spindle and in contact with said first-named bar, a resilient arm secured to the outer terminal of said spindle, and a stop for said arm, the construction and arrangement of parts being such that, when said arm is moved from one side to the other of said stop, said first-named bar is shifted to move said lock-bars out of the way of said shank, and, when said arm is moved back, said first-named bar is shifted to permit said lock-bars to assume their former positions.

12. In a lock of the class described, a lock case, a plurality of serrated lifter-bars, means to elevate said lifter-bars individually, and a single spring fastened to said case, and cut to form a plurality of detents each engaging one of said lifter-bars.

13. In a lock of the class described, a lock case, a plurality of serrated lifter-bars, means to elevate said lifter-bars individually, said means including resilient detents, a drop-bar having arms which are pivotally connected with said case, and are provided with a rod located behind said detents, a link pivotally connected with the front of said case, and extending through said drop-bar and a handle pivotally connected with said link, and adapted, when swung in one direction on its pivot, to exert a cam action on said drop-bar and thereby operate the same to cause said detents to be drawn away from said lifter-bars.

DARIO ROBERTI.
